(57) **CLAIM**

I claim the ornamental design for a bird feeder, as shown.

DESCRIPTION

FIG. 1 is a top perspective view of the bird feeder of the present invention.

FIG. 2 is a top exploded perspective view of the bird feeder of the present invention.

FIG. 3 is a front elevational view of the bird feeder of the present invention.

FIG. 4 is a right side elevational view of the bird feeder of the present invention.

FIG. 5 is a back side elevational view of the bird feeder of the present invention.

FIG. 6 is a left side elevational view of the bird feeder of the present invention.

FIG. 7 is a top plan view of the bird feeder of the present invention.

FIG. 8 is a bottom plan view of the bird feeder of the present invention.

FIG. 9 is a top perspective view of the bottom piece of the bird feeder of the present invention shown alone for clarity; and,

FIG. 10 is a top plan view of the bottom piece of the bird feeder of the present invention shown alone for clarity.

The portions shown in broken line are for illustrative purposes only and form no part of the claimed design.
